UNITED STATES PATENT OFFICE.

ERNEST C. FOX, OF CLEVELAND, OHIO.

THIMBLE STRUCTURE FOR PARTITIONS.

Application filed November 10, 1922. Serial No. 600,150.

This invention relates to a thimble structure for walls of buildings, such as partitions or floors, and particularly, to such a structure especially adapted for use in connection with registers and ventilator face plates.

The object of the invention is to provide an improved thimble structure of the class described which comprises a series of telescoping thimbles of substantially equal length, so that said structure is not only readily extensible to any desired length, but when not in use may be readily collapsed, thereby not only minimizing the space necessary therefor in shipping and storing the same, but materially strengthening the structure and minimizing the liability of damage thereto in handling or storing the same; which structure is easily and quickly mounted in a wall, such mounting being effected from one side thereof; and which structure readily accommodates itself to variations in alignment of the opposed openings in the wall.

Further objects of the invention are in part obvious and in part will appear more in detail hereinafter.

In the drawing, which represents one suitable embodiment of the invention, Fig. 1 is a vertical sectional view of my improved thimble structure mounted in the floor of a room the thimble members being provided with the usual ventilating grids; Fig. 2 is a side view of the structure in collapsed position, the view being partly in elevation and partly in section; and Fig. 3 is a fragmentary plan view with the register removed.

Referring to the drawing, 1 represents the floor of a room, 2 the ceiling of a room below, and 3 and 4 opposed openings in the floor and ceiling, respectively. Suitably mounted in the openings in said floor and ceiling is my improved thimble structure which comprises a series of telescoping, rectangular thimbles, preferably three or more, three being shown, which thimbles are made of any suitable material, such as light sheet metal. Said thimbles are of such cross dimension as to snugly fit within the correspondingly shaped openings 3, 4 in the floor and ceiling, and are of such height that when they are in extreme extended or assembled position, substantially as indicated in Fig. 1, their combined height is greater than the maximum thickness of the usual partition or

floor or ceiling, each of said thimbles being preferably substantially equal in height.

Said thimble structure comprises two end thimble members 5, 6 and one intermediate thimble member 7, said thimbles being telescopically arranged, with end thimble 5, for example, the largest in cross section, and end thimble 6, the lowest one in Fig. 1, the smallest. Each of said end thimbles is provided at its outer end with an outwardly extending flange, flange 8 of thimble 5 being adapted to engage the floor 1 around opening 3, and flange 9 of thimble 6 being adapted to engage the ceiling 2 around opening 4, when the thimble structure is mounted in the floor and ceiling, as indicated in Fig. 1, the means for securing said structure therein being hereinafter described.

Said intermediate thimble 7, which is adapted to slide or telescope within floor thimble 5, is provided at its upper end edges with outwardly and downwardly extending flanges which are adapted to engage or co-operate with inwardly and upwardly extending flanges at the lower or inner end edges of thimble 5, so as to provide interlocking connections 10 between thimbles 7 and 5. While telescoping movement of said thimbles is freely permitted, longitudinal separation thereof is prevented, at one end by the interlocking flanges 10, and at the other end, the upper or outer end of thimble 5, by an inwardly extending flange 11, which may be an integral part of floor engaging flange 8 or a separate flange suitably secured thereto, as shown, the primary purpose of said inwardly extending flange 11 being to center the register secured in the outer end of thimble 5, as will later appear. When the thimble structure is assembled and mounted in a partition, or in a floor and ceiling, as shown in Fig. 1, the lower end portion of intermediate thimble 7 engages or is sleeved over the upper end or ceiling portion of lower end thimble 6, so that the passage within the thimble structure is closed from the space between the walls of the partition or the floor and ceiling, and the air passing through said passage is prevented from escaping.

Usually but one intermediate thimble is utilized, but more may be used if desired, especially where unusually thick partitions or floors and ceilings are encountered, it being inadvisable to materially increase the

height of any or all of the several thimbles by reason of the fact that greater space would be required in shipping and storing the structure, and also because said structure 5 would thereby be materially weakened so that the liability of damage thereto in handling or storing the same would be consequently increased.

Said thimble structure is secured or held 10 in place in the floor and ceiling with flange 8 of thimble 5 engaging the floor and flange 9 of thimble 6 engaging the ceiling by means of a pair of coiled springs 12, suitably secured to the inner faces of opposed wall 15 portions of the lower ceiling thimble 6, the outer free ends of said springs being provided with suitable hook portions adapted to be secured in suitable apertures 13 in opposed wall portions of the upper floor 20 thimble 5.

Both end thimbles carry the usual ventilating grids, the grid or ventilator plate 15 for the lower thimble being secured to the ceiling engaging flange 9 of thimble 6, such as 25 by the bolts and nuts 14. Opening 3 in floor 1 is covered by a removable register grid, one preferred standard form being indicated at 16. Said register is rectangular in shape and is provided with the usual pivoted slate 30 17 for opening and closing the passage therethrough.

The above described device embodying my improved thimble structure is installed or mounted in the floor and ceiling, as indicated in Fig. 1. Registered grid 16 is removed and the end thimble 5 and intermediate thimble 7 are now inserted into the floor opening 3, with flange 8 of thimble 5 engaging or resting upon the floor around said opening, intermediate thimble 7 being supported by end thimble 5 by reason of the interlocking flanges 10 therebetween. Ceiling thimble 6 with its attached ventilator face plate 15 is then passed through the open center of thimble 5 and thus through floor opening 3 and ceiling opening 4, being easily held by the hands of the workman on floor 1. The body portion of said thimble is then inserted upwardly into ceiling opening 4 so that the outwardly extending flange 9 of said thimble and the attached ventilator face plate 15 engage the ceiling 2 around the opening 4 therein and the upper portion of the ceiling thimble surrounds the lower portion of the intermediate thimble 7. The hook portions of springs 12 are then grasped and hooked into the apertures 13 in floor thimble 5, thereby firmly securing the thimbles in place. Register 16 is then inserted in the upper end of thimble 5 with the

marginal portion of said register engaging or resting upon the floor engaging flange 8 thereof, both register 16 and ventilator face plate 15 being then substantially flush with the floor and ceiling, respectively. 65

It will thus be seen that I have provided an improved thimble structure for partitions or floors and ceilings which is especially adapted for use in connection with registers and ventilator face plates, and which thimble structure, together with the register and ventilator face plate, may be quickly and easily mounted in the floor and ceiling of an upper and a lower room from the floor of the room above. The structure may therefore be secured in a wall, such as a partition or floor, by only one workman. Moreover, the structure is readily extended and adjusted to the proper length, and when not in use, may be readily collapsed to exceedingly compact form. Furthermore, the structure, by reason of its series of telescoping thimbles, readily accommodates itself to variations in alignment of the opposed openings in the floor and ceiling, as will be 80 readily understood.

Having described my invention, I claim:

1. A ventilating thimble for securement in a wall having a through opening extending from one face to the other, comprising two end thimble members adapted to be mounted at opposite ends of said opening against the opposite faces of the wall, each of said members being provided at one end with an outwardly extending wall face engaging flange, 90 one of said members being open and the second being constructed and arranged to be passed bodily through the wall opening from one side and thence to its seat on the opposite side of the wall, and means operable through the opening of the open member for interconnecting said members so as to maintain them in the wall opening with their flanges engaging opposite wall faces. 95

2. A ventilating thimble of the character described in claim 1, provided with an intermediate thimble member telescopically related to and carried by one of said end members and adapted to telescope the other and span the gap between them when in place in the wall opening. 100

3. A ventilating thimble of the character described in claim 1, provided with a ventilating grid removably associated with said open end member and lying over the opening thereof. 105

In testimony whereof I hereby affix my signature.

ERNEST C. FOX.
